UNITED STATES PATENT OFFICE.

LESLIE W. CLAYBOURN, OF MENASHA, WISCONSIN.

METHOD OF CORRECTING PRINTING PRESSES.

Application filed February 6, 1922. Serial No. 534,348.

To all whom it may concern:

Be it known that I, LESLIE W. CLAYBOURN, a citizen of the United States, residing in the city of Menasha, in the county 5 of Winnebago and State of Wisconsin, have invented certain new and useful Improvements in Methods of Correcting Printing Presses, of which the following is a specification.

10 My invention relates particularly to method of correcting the printing couples of printing presses comprising either a reciprocating bed or a rotating cylinder, or both such bed and cylinder.

15 I have exemplified my invention as applied to a printing press employing reciprocating type-beds and rotating tympan cylinders coacting with the beds in a so-called two-revolution two-color printing press, al- 20 though it will be obvious that my invention is employable in other relations.

I have found that best printing results 25 are obtained when the periphery of the cylinder represents a true cylindrical surface concentric with its axis of rotation and the type-supporting surface of the reciprocating bed is in a true plane parallel with the axis of rotation of the cylinder, and it is the object of my invention to obtain this desirable 30 condition.

It has heretofore been a practice to separately operate upon the guideways of the frame for the bed, upon the guideways at the underface of the bed, the intermediate 35 anti-friction mechanism therefor, and the type-surface of the bed, as well as upon the peripheral surface of the cylinder and the journals and bearings therefor, and to thus attempt to obtain a parallel relation between 40 the peripheral surface of the cylinder and the type-surface of the bed during the operation of the printing press, with the result that variations incident to the separate operations and incident to a lack of true relation in assembling, have resulted, making a 45 large amount of make-ready necessary for proper printing upon the press.

The printing pressures exerted by printing presses in printing operations as heretofore usually conducted are very great, causing additional variations between the peripheral surfaces of the cylinder and the type-surface of the reciprocating bed, due to 50 displacement of the metal in the parts, and additional variations are in course of time 55

created in the printing press by the wearing action of the printing pressures between the tympan cylinder or cylinders and the type-bed or beds.

In practice the bed reciprocates upon anti-friction devices, such as rollers or so-called sliders, embracing a slider-frame and anti-friction rollers therein, and in practice the greater portions of the printing pressures due to the make-ready and also the greater 60 amount of printing takes place at or adjacent to the middle of the bed, resulting in course of time in a depression of the middle portion of the bed and a depression of the middle portion in the length of the cylinder, 65 so that whatever cylindrical form the cylinder initially had, and whatever plane surface the type-bed initially had, are lost and the surfaces distorted, the result being a hollow bed or beds and a cylinder of less diameter at its middle portion than at its end portions. 70

Under the general designation type I include separable type, lines of type, plates, blocks and other printing surface supporting means. In a two-cylinder printing press, such as exemplified, there is a type-bed 80 for each cylinder, instanced however as connected for combined movements.

It is the object of my invention to correct 85 such undesirable conditions due to methods of building and assembling printing presses heretofore in use and due to the wear hereinbefore described.

It is the object of my invention further 90 to provide a new and improved method whereby to produce supporting surfaces for the type and tympan sheets, which shall be equidistant throughout their printing moments, measured by printing pressures, so as 95 to obtain equal printing pressures upon the printing surfaces throughout their areas and whereby further ideal printing conditions are produced for employment of the printing plates shown, described and claimed in 100 my copending application for patent on improvements in method of correcting printing plates and printing plates produced thereby, Serial No. 453,665, filed March 19, 1921, and, further, as one of the steps in my improved system of printing.

For accomplishing such object, I have conceived the method of finishing the type-supporting surface of the type or plate-supporting member of the printing couple, in- 110

- 2
- stanted as the type-bed, and the peripheral surface of the cylinder, after the printing press has been assembled and is operable for printing purposes, so as to correct said members in their operative relations to each other, and further, to correct printing presses which have been in operation and in which improper relation between the type-supporting surface and the peripheral surface of the tympan cylinder has been accentuated by wear, and further, to cause such corrections to take place under substantial printing pressures.
- It is the object of my invention, further, to correct the type-bed or type-beds and the cylinder or cylinders by finishing their denuded supporting surfaces during movements of said members similar to their printing movements, or in substantially their printing relations, though not necessarily at printing distance from one another or at printing speeds or printing directions; further, to provide novel means for accomplishing said purposes; further, to employ the operating devices for said bed and cylinder in the truing operations. The terms printing relation and operative relation where they occur in the description and claims herein mean such relation as to result in movements of the respective members of the printing couple similar to their respective movements in performing their printing functions though not necessarily in printing proximity or at printing speeds or in printing directions. The speeds and directions of movement of the respective members of the printing couple during correction thereof by my method are desirably such surface speeds and directions as are adapted for the tools and the positions of the tools employed in correcting. The invention will be further readily understood from the following description and claims, and from the drawings, in which latter:
- Fig. 1 represents a diagrammatic longitudinal section of a printing press, showing the inaccuracies in magnified form due to wear, for the purpose of illustrating defects corrected by my invention.
- Fig. 2 is a diagrammatic representation of a cross-section of the same, showing such defects in magnified form for similar purposes.
- Fig. 3 represents a side elevation of so much of a two-revolution two-color printing press as is necessary to illustrate my invention, and having my improved apparatus applied thereto.
- Fig. 4 is a reverse side elevation of the same.
- Fig. 5 is a plan view of the same.
- Fig. 6 is an end elevation of the same.

I do not herein claim means or apparatus which may if desired, be employed in performing my improved method, or the means or apparatus herein shown and described, having shown, described and claimed the same in a copending application, divisional hereof, for apparatus for correcting printing presses, filed in the United States Patent Office December 17, 1923, as Serial No. 681,237, to which reference is made for a more full exposition of said means and apparatus and the claims thereto. 110

My invention is shown applied to a two-revolution two-color flat-bed printing press, although the same is applicable to other printing presses. The exemplified printing press comprises the beds 21 and 22, which are connected for operating purposes and reciprocate in unison respectively under tympan cylinders 23, 24. The beds comprise the bed-sections of a bed structure, 115 120 125 130

Each of the beds is provided with side bearers 25.

The printing press has a usual main frame, comprising side frames 31, and cross-girts 32, 33, which have tracks 35, 36, 37, 38, thereon, extending longitudinally of the frame, the cross-girts comprising uprights 39 on which the tracks 37, 38, are supported.

Anti-friction devices are located between 10 the type-beds and the tracks, exemplified as sliders, each of which comprises a framework 41, and anti-friction rollers 42, which roll on the tracks. Tracks 45, 46, 47, 48, on the under surface of the bed, ride on the 15 rollers of the sliders.

The tympan cylinders are provided with trunnions 51, 52, journaled in bearings 53, 54, eccentrically journaled in bearing-blocks 55, 56, respectively adjustable by adjusting 20 screws 57, 58, and 59, 60, in guideways 61, 62, in standards 63, 64, of the frame, suitable means being provided for raising the impression cylinders into off-impression relation or causing their descent into on-im- 25 pression relation to the beds at alternate revolutions of the cylinders or as desired, in the usual operation of the printing press, accomplished for instance by means of links 66, 67, articulated with arms 68, 69, 30 extending from and rigid with the eccentric bearings. The lower ends of the links are operated by usual cam and lever mechanism having operative connections with usual cam-disks 71, 72, suitably rotated in the 35 usual operation of the printing press.

Each of the tympan cylinders comprises side bearers 73, which coact with the side bearers 25 on the beds. The usual tympan sheets and covering are received over the 40 peripheral surface of the cylinder in the recess between the side bearers thereon, and the type are received on the supporting surface of the bed between the side bearers thereon. The contact faces of the side bearers which coact with each other are intended 45 to be in the plane of the printing surfaces of the type at the printing moment.

A transfer cylinder 76 is located between the tympan cylinders and may be of usual 50 construction.

The sheets to be printed are arranged to be fed to the first tympan cylinder 23 from a feed-board 78, the sheet being arranged to be gripped by suitable grippers on the cylinder and carried around the cylinder in the direction of the arrow *a* for the purpose of being printed, in the usual manner, the bed 21 of the first printing couple moving in the direction of the arrow *b* in this printing 55 operation.

After being printed by the first printing couple, the sheet travels with the cylinder 23 in its rotation until the advanced edge of the printed sheet arrives at the transfer cylinder 76, when it is released by the grippers 60

of the tympan cylinder 23, and gripped by the grippers of the transfer cylinder 76, and carried in usual manner with the transfer cylinder in the direction of its rotation, the direction of which is indicated by the 70 arrow *c*, to the tympan cylinder 24, of the second printing couple.

Upon arrival of the advancing edge of the sheet at the tympan cylinder 24, the said advancing edge is released by the grippers 75 of the transfer cylinder and grasped by the grippers of the second tympan cylinder, and then carried about the second tympan cylinder in the direction of its rotation, indicated by the arrow *d*, the sheet being printed 80 by the printing surfaces on the bed 22, when the sheet arrives between the tympan cylinder 24 and the bed 22, the bed of the second printing couple moving in the direction of the arrow *e* during the printing 85 operation.

The sheet is then carried with the tympan cylinder 24 until it arrives at the delivery mechanism, the stands of which are indicated at 81, where it is transferred to the 90 delivery mechanism for delivery of the sheet.

The structures of these parts and their operations may be of any usual or ordinary kind. The grippers are not shown, as the 95 same have been removed for the purpose of having my improved apparatus operate upon the tympan cylinders. It will be understood that only so much of the printing press is shown as is concerned with the performance of my improved method thereon. 100

In the usual printing operation of the printing press the printing surfaces supported by the bed-sections are suitably inked by suitable form rollers, suitably placed, 105 and supplied with ink in any ordinary or well-known manner, for instance, from usual ink tablets, not shown, but normally secured to the outer ends of the beds, supplied with ink by coaction with suitable ink distributing and ink supplying rollers, the initial ones of which are shown respectively as fountain rollers 85, 86, at the respective ends of the press, to which intermittent motions are imparted by any ordinary or well-known means. 110

I have exemplified the means for rotating the cylinders, for reciprocating the bed-sections, and for intermittently rotating the fountain ink rollers as follows: A driving shaft is exemplified at 91, and is arranged to have suitable driving means, exemplified as a tight pulley 92 and a loose pulley 93, over which a suitable belt from a suitable source of power is arranged to be selectively received. 120

A gear 94 is fixed on the driving shaft and meshes with a gear 95, fixed on a shaft 96, journaled in the frame. The gear 95 meshes with a gear 97, journaled on a stud 130

98 fixed to the frame. The gear 97 meshes with a gear 99 fixed to one of the trunnions of the tympan cylinder 24. The gear 99 meshes with gear 101 fixed to a shaft 102 of the transfer cylinder 76.

A gear 103 is fixed to one of the trunnions of the tympan cylinder 23 and meshes with the gear 101.

The drive-shaft 91 is arranged further to 10 reciprocate the bed by any well-known mechanism, instanced as accomplished by means of a pinion 108 which rotates with the shaft 96, but has spline-connection therewith, and arranged to be alternately brought 15 into mesh, by axial shifting thereof on its shaft by any well-known mechanism, with racks 109, 110, extending lengthwise of the bed-structure, on which both bed-sections are located, and supported respectively by 20 the bed-structure and by a hanger 111 depending from the bed-structure, for alternately driving the bed-structure in reverse directions.

Intermittent rotation is shown imparted 25 to each of the fountain rollers. This may be accomplished by means of a link 116, one end of which has articulation with a crank-pin 117 on one of the cam-disks 71, 72, which are employed for imparting the desired 30 movements to the eccentrics for controlling the on-impression and off-impression relations of the tympan cylinders. The other end of the link 116 has articulation with a lever 119, journaled about the shaft 120 of the fountain roller; this shaft being journaled in bearings 121 of end frames 122 of the respective ink fountains 123, 124.

A ratchet-wheel 125 is fixed to this shaft. A pawl 126, pivoted to the lever 119, is urged 40 towards said teeth by a spring 127 engaging a pin 128 on the pawl. When the link moves the lever in one direction, an idle movement of the pawl with relation to the ratchet-wheel takes place, and when the 45 lever is moved in the opposite direction, the pawl engages one of the teeth of the ratchet-wheel for partially rotating the fountain roller. A spring detent 129 is arranged to engage notches 130 in a disk 131, fixed to the 50 shaft of the fountain roller, for holding the fountain roller in actuated relations.

In order to control the degrees of movements of the fountain roller, a cover-cam 134 is provided, having a cover-periphery 55 135 extending outwardly beyond the ratchet-teeth to cause the pawl to ride thereon when the cover-portion is in the range of the pawl. The cover-cam is adjustable about the shaft of the inking roller, and is arranged to be 60 held in adjusted positions by means of a clamp-screw 136, received in an arcuate slot 137 in a tail-piece 138 of the cover-cam, and arranged to clamp the tail-piece to one of the end-frames of the inking fountain for 65 holding the cover-cam in adjusted positions,

to determine the number of teeth of the ratchet-wheel which shall be exposed to the action of the pawl, and thereby determine the angular distances of rotation of the inking roller at each rotation thereof.

The parts and operative devices of the printing members hereinbefore specifically described are such as are usual in printing presses of this character, and the same or other usual devices usually employed in their 70 stead may be employed in carrying out my invention.

Referring to Figs. 1 and 2, representing 75 diagrammatically the inaccuracies described prevalent in printing presses, the type-supporting surface 141 of the type-bed is denuded of its type including all printing surface supporting elements, and the supporting surface 142 of the tympan cylinder is shown denuded of the tympan sheets and 80 tympan covering means, to expose said surfaces.

It will be noted that depressions are present 85 in the type-supporting surface of the type-bed and in the peripheral surface of 90 the tympan cylinder. The type-bed is exemplified as hollowed toward its middle, as shown at 145. It is assumed that such of the rollers 42 and the tracks therefor under 95 the bed as have become worn have been renewed by replacement, or refinishing, for proper travel of the bed. Any such wear is greatest under the middle portion of the bed. The middle portion of the type-bed in practice receives the greatest printing pressures, as well as has the greatest amount of 100 printing pressures exerted thereon, due to the fact that in practice the printing forms, whether large or small, are usually located toward the middle portion of the type-bed. 105 For similar reasons the tympan cylinder has depressions formed therein, represented as a hollow 148 toward the middle of the tympan cylinder.

These deformities are accentuated in Figs. 110 1 and 2, from what they are in actual practice, in order to clearly show the defects which are corrected by my invention, other defects being variations due to the separate 115 finishing of coacting surfaces and operating and supporting parts in the making of printing presses as heretofore usually constructed.

I shall now describe a mechanism which may if desired be employed in performing 120 my method, although other mechanism or manipulation may be utilized in performing the same. This mechanism is exemplified as employed in correcting the type-supporting surface of the bed, and the peripheral surface 125 of the tympan cylinder. I have in Figs. 3, 4 and 5 (see also Figs. 8 and 9), exemplified one of these apparatuses with its finishing tool presented toward the bed of one of the printing couples at one end of the printing press, and another of the apparatuses with 130

its finishing tool presented toward the cylinder of the other of the printing couples at the other end of the printing press. When correcting the printing press, I prefer to remove those portions thereof which might be in the way of the finishing operations and are not concerned therein, including the distributing rollers and the form rollers of the inking mechanism and the stands therefor.

10 I prefer to provide the correcting apparatus with supports arranged to be attached to the frame of the printing press and supporting a guideway for the finishing tool in such manner that the finishing tool may be presented to the bed or to the cylinder without disturbance of the supports so that when the supports have been secured to the frame in such manner that the feeding motion of the finishing tool is parallel with the axis of 75 rotation to the cylinder, such setting may be employed for finishing both members of the printing couple, instanced as the cylinder and the bed.

15 Thus I employ a pair of supports 151 arranged to be secured to the side frames of the main frame of the printing press, for instance, by means of bolts 152 received through slots 153 in the supports and threaded into threaded holes in the side frames, which may be the threaded holes used to connect the bearings for the form 80 rollers to the side frames.

20 A cross-rail 155 is supported on the supports, preferably in such manner as to permit the cross-rail to be angularly adjusted on the supports for presenting the tool thereon either to the bed or to the cylinder. For this purpose I provide the supports with grooves 156 in which tongues 157, 158, 25 on the cross-rail are arranged to be received, for positioning the cross-rail definitely with relation to the supports.

25 A cross-slide 161 is fed lengthwise of the cross-rail; that is, transversely of the printing press, being guided in such travels by guides 162, and 163, on the cross-rail coacting with guideways 164, 165, in the cross-slide. The guide 162 and its complementary guideway are shown as square and the 30 guide 163 and its complementary guideway are shown as tapering, comprising a take-up gib 166, acted upon by take-up screws 167 for adjusting the sliding contact in the guides and guideways, jamb-nuts 168 fixing 35 the adjusting screws in adjusted positions.

35 Feeding movement is imparted to the cross-slide by means of a cross-feed screw 171 of fine pitch having threaded connection with a nut 172 secured to the cross-slide. A ratchet-wheel 173 is fixed to the cross-feed screw. The feed screw is journaled at its respective ends in bearings 174, in the cross-rail.

40 45 50 55 60 65 A rockable lever 176 is journaled about the feed-screw, and has a pawl 177 pivoted

thereon, which is arranged to engage the teeth of the ratchet-wheel, and is normally pressed toward such teeth by a spring 178.

60 A link 180 is articulated with the rockable lever by an articulation 181, and has a reciprocating movement imparted thereto by a reciprocating part of the printing press, instanced as the lever 119, which imparts intermittent rotary motion to the fountain roller. This connection is preferably an 70 adjustable connection for adjusting the distances of steps of feed of the cross-slide, in addition to the adjustment heretofore described for adjusting the extents of rotative movements of the fountain roller.

75 In order to accomplish this, I provide an arm 182, having operative connection in manner hereinafter described, with the shaft 120 of the fountain roller, to impart intermittent rotary movements to the cross-feed 80 screw 171. This arm is provided with a slot 184. The link 180 is received through an eye 185, arranged to be clamped in adjusted positions lengthwise of the link by means of a set-bolt 186. The eye is swivelingly 85 mounted by a swivel 187, at the head end of a bolt 188, received through the slot 184, a clamp-nut 189 clamping the bolt in adjusted positions lengthwise of the slot 184.

90 When now the printing press is placed in 95 operation for operating the parts remaining therein and concerned in the correction of the printing press, reciprocating motion is imparted to the lever 119 by means of the crank-pin 117 and link 116, which reciprocating motion is in turn imparted as an intermittent rotary motion by the arm 182 to the tool-feeding mechanism.

100 A tool-slide 191 is adjustable transversely of the cross-slide in a guideway 192 by 105 means of an adjusting screw 193 journaled in a lug 194 in the tool-slide, in which the adjusting screw is held endwise, and having threaded engagement with the cross-slide. This adjusting screw preferably has a fine 110 pitch for minute adjustment of the finishing tool toward and from the surface being finished, the degrees of adjustment being determined by means of the graduations of an index 195.

115 I preferably employ a clapper-box 197, pivoted to the tool-slide at 198, in which to mount the finishing tool, exemplified at 199, by means of a tool-post 200, having a clamp-bolt 201, by means of which to fasten the 120 finishing tool to the clapper-box. This finishing tool is exemplified as a scraping tool, to provide the metal of the supporting surfaces of the bed and cylinder with a smooth surface.

125 In employing my improved method for correcting printing presses, I first replace any worn rollers and tracks therefor there may be under the type-bed, or correct the same, for providing a proper foundation for 130

the travel of the bed. I then adjust the tympan cylinder in true horizontal relation or as parallel to the horizontal relation of the bed under printing pressures as possible, although adjustment to printing distance is not necessary. I mount the supports 151 on the side frames and insert the bolts 152 and thread the same into said side frames. These supports are so adjusted as to cause 10 the grooves 156 therein to be parallel with the axis of rotation of the cylinder, so that the feeding movement of the cross-slide on the cross-rail supported by the supports shall be parallel to such axis of rotation in 15 order that the periphery of the cylinder may be finished as a true cylinder having the axis of rotation coincident with its axis.

The positioning for parallelism of the cross-rail may be obtained, for instance, by 20 a suitable gauge 205, having a pointer 206 received in the center mark of one of the trunnions of the cylinder, and having another pointer 207, adjustable thereon, by means of being mounted in a slot 208, and 25 clamped in adjusted positions by means of a nut 209 received over a threaded shank 210 in said slot and having a shoulder 211, the body of the gauge being clamped in adjusted positions between the nut and the shoulder. The pointer 207 is caused to be received in the center mark in the end of the feed-screw.

The pointers being adjusted to the desired distance, and the cross-rail and its supports having received a preliminary fastening for placing the cross-rail in proximate parallelism to the axis of rotation of the cylinder, the definite adjustment of the cross-rail may be accomplished by employment of the gauge, held perpendicular to the axis of rotation to the cylinder, and causing the punch marks in the respective ends of the feed-screw to register with the pointer 207 of the gauge, while the pointer 40 206 thereof is held in the center punch mark of the trunnion at the same side of the press. The operation is repeated at opposite sides of the press, and the adjustments continued 45 until the desired result is obtained.

50 A definite positioning of the supports may be had by tapping upon the same in order to shift the support on the side frame for causing proper positioning of the support with relation to the cylinder determined by 55 the gauge in the manner described. The clamp-bolts may then be fastened and the parallelism again tested by means of the gauge. Similar operations may be performed at each end of the cross-rail.

60 The cross-rail is secured to each of the supports by means of clamp-bolts 214 received through apertures 215 in the top wall 216 of the support and threaded into the cross-rail.

65 When the supports have been positioned

and clamped in place, they are not again disturbed until the finishing operations upon the pair of members of the printing couple, instanced as the bed and the cylinder coacting therewith, have been completed. The 70 cross-rail is merely turned upon the supports for presenting the tool thereon either to the bed or to the cylinder. This turning of the cross-rail is shown accomplished in Figs. 3, 4, 8 and 9, by means of causing the tongues 75 157, 158, to selectively register with the grooves 156. These tongues and the grooves, being parallel with each other, position the cross-rail for parallelism of cross-feeding movement of the tool, whether presented to 80 the bed or to the cylinder. This construction further forms a rigid construction in which the cutting function of the tool is resisted by substantial means adjacent to the cutting edge of the tool and constructed in such 85 manner as to avoid yield and chatter. The cross-rail is represented as a heavy cored casting.

The clapper-box for supporting the tool is 90 especially useful when finishing the bed for permitting the cutting edge of the tool to retreat upon retracting movement of the bed and causing the tool to return to cutting position upon advancing movement of the bed during the cutting operation. In order 95 to provide for the guideway adjacent to the tool between the cross-rail and the cross-slide, I prefer to mount the tongues 158 on end-walls 217 extending from the body 100 of the cross-rail.

When the truing mechanism is transferred from one printing couple to the other, it is reversed end to end.

I have found it desirable to remove the 105 chips and refuse caused by the cutting tool as soon as formed, in order to keep the surface being finished clear of chips and refuse, especially when employing the pressure devices hereinafter described. For this purpose I prefer to employ a powerful suction device, comprising a mouth 221 adjacent to the tool. The mouth communicates with a channel 222, in an arm 223, secured at 224 to the tool-slide and having connection with a suitable suction device to 110 create a powerful suction in said passage.

As hereinbefore stated, it is one of the objects of my invention to true the bed in its printing relation, that is, while in reciprocating relation in the printing press, and to true it in such manner that the surface relation between the type-supporting surface of the bed and the peripheral surface of the cylinder shall be a parallel relation, 115 parallel with the axis of rotation of the cylinder, when said surfaces are subjected to printing pressures. If it is desired to exert additional pressure upon the bed to additionally hold the bed down firmly upon its rollers or supports or to exert substan- 120 125

tial printing pressure relation upon the bed during the correcting operation, I provide a presser device which exerts pressure upon the surface of the bed while the same is being finished.

This presser device is instanced as including a cross-rail 228, having depending supports 229. Bolts 230, 231, pass through slots 226, 227, in the supports and are 10 threaded into suitable threaded holes in the side frames, for adjustably fixing the supports to the side frames. These threaded holes may be the ones usually employed for attaching the inking roller bearings to the 15 side frames. Rollers 232 are provided with trunnions 233, journaled in bearings 234 of forks 235, there being a suitable number of these rollers arranged cross-wise of the bed for exerting pressure throughout the width 20 of the bed.

Each of the forks is mounted on a plunger 236, movable axially in a bearing 237 of the cross-rail 228, and prevented from turning therein by being provided with a key 238, 25 received in a slot 239 in the bearing. A stem 241 extends from the plunger and has a heavy helical spring 242 received thereabout within the bearing 237. A sleeve-nut 243 has threaded connection with the upper 30 end of the bearing 237, the stems 241 being reciprocable in the sleeve-nut.

The hold-down device is instanced as independent of and as having no connection with the truing device, so that no vibrations 35 of the pressure hold-down device may be communicated to the truing device.

While I have in Figs. 5, 8 and 9 exemplified a metal scraping tool or finishing tool, having a scraping or finishing edge, as the 40 finishing tool of preferred form, it is obvious that other finishing tools may be employed, and that, for instance, a grinding wheel may be employed for finishing purposes.

I have shown such grinding wheel in Figs. 45 20 to 23, as used in place of the scraping tool, the other parts of the mechanism being substantially the same and indicated by similar reference numerals with the exponent prime. Thus I mount a grinding wheel 248 on a shaft 249 journaled in bearings 250 of a tool-slide 191'. These bearings may be part of an electric motor frame and the rotation of the grinding wheel accomplished by an electric motor 251, of which the shaft 50 249 may be the armature-shaft. This grinding may be accomplished either wet or dry, as may be desired, suitable means being provided for preventing access of the grinding refuse into working parts of the press, 55 and the refuse removed by suction device similar to the suction device when employing the finishing tool.

The beds and cylinders are, during the truing operations, preferably operated by 60 the means employed for operating the same

in their printing functions. The cylinder 23 is shown rotating in the direction of the arrow α during its printing function. When rotating this cylinder during the truing operation thereon, it is preferably rotated in 70 opposite direction.

The entire widths of the supporting surfaces of the tympan and type-bed are preferably trued by employment of my improved method. When truing the bed it is preferable 75 that the inking table thereof be removed, the pressure rollers bearing upon the supporting surface and the surface under the inking table during the truing operation. When truing the bed, its side bearers 80 may also be removed.

The bearers of the cylinder and bed are reduced or corrected preferably while respectively on the cylinder and bed, to conform 85 to the reductions or corrections made upon the cylinder and bed respectively. The reductions or corrections of the bearers are made by the same correcting devices used in correcting the denuded supporting surfaces of the bed and cylinder while still attached to the frame of the printing press, and while the bed and cylinder are respectively moved in substantial printing relation preferably by the operating parts of the 90 printing press. The correction of the bearers of the bed may take place while the bed is held under substantial printing pressure.

The operative connection between the shaft 120 of the fountain roller and the arm 182, for imparting an intermittent motion to the 100 arm 182, may be accomplished as follows, referring to Figs. 13, 16, 17, 18 and 19.

The arm 182 has a bearing 254 about the shaft 120, and is held to said shaft by a collar 255, fixed to the shaft by a set-screw 256. 105 A ratchet-wheel 257 is fixed to said shaft by a set-screw 258. A pawl 261 is pivoted to the arm on a pin 262 and is provided with a heel 263 and a tripper-pin 264. The awl is arranged to be brought into engagement 110 with one of the teeth of the ratchet-wheel for movement of the arm 182 in operating direction, and is arranged to be moved out of engagement with said tooth at the completion of its operative movement, the arm 115 being arranged to be automatically returned to initial position to be again engaged by a tooth of the ratchet-wheel at the next intermittent rotary movement of the shaft 120.

The extent of this intermittent rotary movement of the shaft 120 is adjustable by means of the cover-cam 134 in manner hereinbefore described. Means are therefore provided to correspond the engaging and disengaging moments of the pawl 261 with 120 the ratchet-wheel 257, with the angular distance of intermittent rotary motion of said shaft 120.

Thus I provide a tripper-cam 266, instanced as on a clamp-block 267, this clamp- 130

- block being of inverted U-form for being received about the end-wall 122 of the ink reservoir, and clamped in adjusted positions to said end-wall by means of a thumb-screw 268. The adjustment moves the tripper-cam 266 toward and from the vertical plane in which the shaft 120 is located in order to be engaged by the tripper-pin 264 on the pawl and thereby determine the moment of disengagement of the pawl from said ratchet-wheel. A spring 269 is secured to the arm 182 and is provided with a hump 270 to co-operate with the heel 263 of the pawl to hold the pawl in engaged or disengaged relation.
- A tripper-part 273 is provided with a tripper-face 274 to engage the tripper-pin in order to re-engage said pawl with said ratchet-wheel. This tripper-part is on a shank 275, provided with a slot 276, through which a set-screw 277 is received, the set-screw being threaded in one of the walls of the inverted U-clamp 267, for adjusting the tripper-face 274 toward and from the vertical plane in which the shaft 120 is located. When the tripper-pin 264 strikes the tripper-face 274, the heel 263 of the pawl is moved to the other side of the hump 270 on the spring 269, for holding the pawl in engaging relation with one of the teeth of the ratchet-wheel. The dotted position of this pawl shown in Fig. 17 shows its position just prior to its tripped relation for engaging the pawl.
- Referring to Fig. 17, the intermittent rotary movements of the shaft 120 take place in the direction of the arrow *f* for moving the arm 182 in operative direction as shown by said arrow, whereby an intermittent rotary motion is imparted to the cross-feed screw 171 in feeding direction.
- At the end of this operative movement, determined by the adjustment of the cover-cam 134, the tripper-pin 264 engages the tripper-cam 266 for disengaging the pawl from the ratchet-wheel, although if desired, this engaging moment may take place prior to the end of intermittent movement of the ratchet-wheel in operating direction, thereby providing additional adjustment of rotary movements of the arm 182, and consequent adjustments of the lengths of steps of feed of the cross-feed screw.
- When the pawl has been disengaged from the ratchet-wheel, the arm 182 is automatically returned to initial position, shown accomplished by means of a spring 280 having one end 281 received in a suitable aperture in the link 180, and its other end 282 received in a suitable aperture in the clamp-block 267, an intermediate coiled portion 283 of the spring being received and positioned loosely about a bolt 284 fixed in said clamp.
- Near the end of such return movement of

the arm 182, the tripper-pin 264 strikes the tripper-cam 274 for again engaging said pawl with a tooth of the ratchet-wheel, preparatory to the next intermittent operative movement of the link 180. The springs 70 cushion the return movements of the arm.

This cross feed screw is provided with attaching means for attaching a hand-crank for operating the cross feed screw by hand and positioning the cross-slide thereon in 75 any desired position. This attaching means is shown as a square end 286 on said cross-feed screw.

Having thus fully described my invention, what I claim as new, and desire to secure 80 by Letters Patent, is:

1. The method of correcting printing couples, which consists in reducing the denuded supporting surface of a member thereof while being operated in substantial 85 printing relation to its mating member.
2. The method of correcting printing couples, which consists in reducing the denuded supporting surface of a member thereof while being operated in substantial 90 printing relation to its mating member and under substantial printing pressure.
3. The method of correcting the supporting surface of a member of a printing couple comprising a rotatable member, which consists in operating said member the supporting surface of which is being corrected in substantial printing relation, and reducing said supporting surface into parallelism with the axis of rotation of said rotatable member while being so operated. 100
4. The method of correcting the denuded supporting surface of a member of a printing couple comprising a rotatable member, which consists in operating said member the supporting surface of which is being corrected in substantial printing relation, reducing said denuded supporting surface into parallelism with the axis of rotation of said rotatable member being so operated, and 105 correcting the bearers of said member being corrected to correspond to such correction.
5. The method of correcting the supporting surface of a member of a printing couple comprising a rotatable member which consists in operating said member the supporting surface of which is being corrected in substantial printing relation, and while so operating reducing said supporting surface 115 into parallelism with the axis of rotation of said rotatable member while held under substantial printing pressure.
6. The method of correcting a printing couple which consists in reducing all portions of the denuded supporting surfaces 120 thereof into parallelism while operating in substantial printing relation.
7. The method of correcting a printing couple which consists in reducing all portions of the denuded supporting surfaces 125 130

thereof into parallelism while operating in substantial printing relation, the denuded supporting surface of one of the members of said couples being so reduced while said member is held under substantial printing pressure.

8. The method of correcting a printing couple which consists in reducing all portions of the denuded supporting surfaces thereof into parallelism while operating in substantial printing relation, the denuded supporting surface of one of the members of said couples being so reduced while said member is held under substantial printing pressure, and correcting the bearers of said members to correspond to said corrections.

9. The method of correcting a printing couple comprising a rotatable member, which consists in mounting and operating said printing couple in substantial printing relation in its printing press, and reducing its denuded supporting surfaces into parallelism with the axis of rotation of said rotatable member while so operating.

25 10. The method of correcting the denuded supporting surface of a member of a printing couple of a printing press comprising a rotatable member, which consists in operating said member the supporting surface of which is being corrected in substantial printing relation, and while being so operated reducing said denuded supporting surface into parallelism with the axis of rotation of said rotatable member, and controlling said 35 reducing by a usual operating part of said printing press.

11. The method of correcting the supporting surface of a reciprocating bed of a printing press which consists in reciprocating said bed in said printing press in usual printing relation and dressing said supporting surface of said bed into a plane surface while so reciprocating.

12. The method of correcting the supporting surface of a reciprocating bed of a printing press which consists in reciprocating said bed in said printing press in usual printing relation while holding said bed under substantial printing pressure and dressing said supporting surface of said bed into

a plane surface while so reciprocating and held.

13. The method of correcting a printing press which consists in operating the same so as to cause usual printing movements of 55 its printing couple and an additional element, reducing the denuded supporting surfaces of the members of its printing couple into parallelism at their successive points of closest approach during said operating, and 60 controlling said reducing by said additional element.

14. The method of correcting a printing press comprising a printing couple including a reciprocating bed, which consists in 65 operating said printing press so as to cause substantial usual printing movements of said printing couple and an additional element, reducing the type-supporting surface of said reciprocating bed into a plane surface by coaction of a dressing tool with said type-supporting surface during its reciprocation and while said bed is held under pressure, and controlling said reducing by said additional element. 70

15. The method of correcting a printing press comprising a printing couple including a rotatable cylinder and a reciprocating bed and each of the members of which is provided with bearers, which consists in 80 operating said printing press so as to cause substantial usual printing movements of said printing couple, reducing the denuded tympan-supporting surface of said cylinder to cylindrical form parallel with the axis of 85 rotation of said cylinder and reducing the type-supporting surface of said reciprocating bed into a plane surface parallel with said axis of rotation by coaction of a dressing tool with said respective surfaces during 90 said rotation and reciprocation respectively, and correcting said bearers to correspond to said reductions of said respective surfaces.

In testimony whereof, I have hereunto subscribed my name in the presence of two 95 subscribing witnesses.
